No. 37,421.

Patented April 25, 1905.

UNITED STATES PATENT OFFICE.

MAUDE MARTIN, OF CHICAGO, ILLINOIS, ASSIGNOR TO MORRIS, MANN & REILLY, OF CHICAGO, ILLINOIS, A FIRM.

DESIGN FOR A LADY'S BELT.

SPECIFICATION forming part of Design No. 37,421, dated April 25, 1905.

Application filed March 27, 1905. Serial No. 252,431. Term of patent 3½ years.

To all whom it may concern:

Be it known that I, MAUDE MARTIN, a citizen of the United States, residing at Chicago, in the county of Cook and State of Illinois, have invented a new, original, and ornamental Design for Ladies' Belts, of which the following is a specification, reference being had to the accompanying drawing, forming a part thereof.

The figure is a perspective view of a lady's belt, showing my new design.

I claim—

The ornamental design for a lady's belt, as shown.

MAUDE MARTIN.
